US00D539174S

(12) **United States Design Patent** (10) Patent No.: **US D539,174 S**
(45) Date of Patent: **** Mar. 27, 2007**

(54) **WATCH CASE**

(75) Inventor: **Irène De Boreīcha Ojjeh**, Geneva
(CH)

(73) Assignee: **De Boreīcha Establishment**, Vaduz
(LI)

(**) Term: **14 Years**

(21) Appl. No.: **29/259,570**

(22) Filed: **May 11, 2006**

(30) **Foreign Application Priority Data**

Nov. 14, 2005 (CH) 132311
Apr. 26, 2006 (CH) 132702

(51) **LOC (8) Cl.** **10-02**

(52) **U.S. Cl.** **D10/38**

(58) **Field of Classification Search** D10/30-39,
D10/122-132; 368/276-278, 281-283, 285
See application file for complete search history.
